STABILIZED COMPARTMENT FOR SHIPS

McCormick Mehan and John I. Markey, Seattle,
Wash.

Application October 21, 1938, Serial No. 236,361

7 Claims. (Cl. 114—191)

Our present invention relates to means for providing a stabilized room aboard a sea-going ship. For persons who of necessity must make sea voyages, seasickness is a very serious as well as distressing malady; and it is the purpose of our present invention to provide means whereby the upsetting effect on passengers, of a ship's rolling about its longitudinal axis or plunging about its transverse axis, will be entirely eliminated, for minor displacement, and will be so minimized in the more extreme displacement that seasickness can be eliminated.

We accomplish this principal object by providing, preferably, at or near the transverse and longitudinal axes of a boat, a room which might be likened to an elevator cage, that will be capable of vertical displacement and at the same time be so mounted and supported that it will within reasonable limits at all times be maintained with its floor in a horizontal plane. There are a number of ways in which this result can be accomplished and in the present application in order to keep to a minimum the drawings and description, we have shown in detail only one physical embodiment of this plan. The mechanical and the electrical means employed in the accompanying drawings, however, can be used with various types of equipment and there must be a reasonable elasticity in the design of such equipment so that it may be adapted to varying conditions as encountered in service.

The physical limitations of a boat may be such that our cage cannot be given full and sufficient travel so as to, in effect, hold the cage on a given horizontal plane. However, for normal disturbances having an amplitude greater than the physical means will permit, our cage is handled in a manner to compensate as fully as possible for the maximum amplitude. In other words the boat will, in effect, move away from the cage then the cage will start to move in the direction of movement of the boat and then gradually come to a rest with respect to the original horizontal plane and experiments which are easily conducted with ordinary passenger elevators in buildings will prove that the average individual will not be able to detect any movement of the cage and as long as this is accomplished there will be none of the sensation created in the individual that leads to seasickness.

Other and more specific objects will be apparent from the following description taken in connection with the accompanying drawings, where-
in

Figure 1 is a perspective view showing the essential elements of our device, namely, the movable room, or cage, and the movable guideways in which it is confined and operated.

Figure 2 is a view showing, partly in section and partly diagrammatically, the electrical means for effecting control of our movable cage and guideways so that the motion of the ship may be adequately counter-acted.

Figures 3 and 3^a illustrate the position of the metacenter about which the majority of ships are designed to roll or pitch.

Figure 4 is a bracketed, diagrammatic view showing the position of our movable guideways and the position of the movable room within those guideways under various stages of rolling caused by a beam sea.

Figure 5 is a similar bracketed view showing a fragmentary section of a ship and showing the position of our guideways and room to counteract the pitching or movement of a boat as it passes through a head or stern sea.

Figure 6 is an elevation showing generally the essential elements required to provide the movement demanded of our equipment.

Figure 7 is a fragmentary view showing the lower portions of our guideways as they are displaced by the pitching of a boat.

Figure 8 is a similar view, but taken as a cross-sectional view through a ship showing the displacement of our guideways due to the rolling action of the ship.

Figure 9 is a view, partly in section and partly diagrammatic, illustrating the switching means and the fluid pistons which control our guideway arrangement.

In general the operation of our device, as we have illustrated the same, consists normally of having vertically disposed guideways 10 mounted in a gimbal joint 12 at a point somewhat above its lower end as shown in Figures 1 and 6. This permits substantially a universal movement for the guideways which are positioned by, preferably, a plurality of fluid operated pistons in cylinders 14.

We then use the electric switching arrangements shown in Figure 9 to control, through solenoids 16 or similar electrical means, the operation of valves 18 which in the present showing control the discharge of oil from the various pistons. The oil supply is normally in a tank 20 from which oil is pumped, as by pumps 22, 23, 24, and 25, and to which it is returned after passing through valves 18. The pumps are operated and controlled by means illustrated, as one ex-

ample, in Figure 9. Here electric switches as 27, 28, 29, and 30, of the mercury tube are controlled by the rolling or pitching of the boat so as to complete an electric circuit which in turn energizes motors 32 directly connected to the pumps; thus pressure can be built up in any cylinder, as each cylinder has its own motor and pump. The discharge is controlled by the same electric circuit and consists of solenoid operated slide cams 34, 35, 36, and 37 which open the discharge valves from the cylinders. In this way rocking of the boat will energize the cylinders required to maintain the guideways in their substantially vertical position.

10 The vertical position of the cage or room with respect to its guideways is controlled by the means shown in Figure 2, in which a spring supported weight 39 is employed in conjunction with photoelectric cells 41 and 42 to energize relays 20 which in turn are so connected as to operate a reversing electric motor 44 in a manner to raise or lower the cage 46 as the portion of the boat containing our device rises or lowers due to either a beam sea, a head sea, or a stern sea. Suitable 25 means are also provided to limit the amount of travel and to reverse the operation automatically.

Detailed operation

30 The operation of our device may be divided into two distinct actions; one is the vertical control of the cage or car and, secondly, its horizontal control. The vertical positioning of the cage is controlled by means probably best illustrated in Figures 1 and 2. Cage 46 is mounted 35 in any conventional manner in guideway 10 so that it will be capable of free guided movement within guideways 10, and will be positioned vertically with respect to the guideways by cable 48 which is arranged for suitable spooling on a 40 drum, controlled by the reversing motor 44 through some appropriate, self-locking reduction gear mechanism as illustrated at 50.

45 The control of motor 44 may be accomplished by means illustrated in Figure 2. This consists essentially of a framework 52 which serves as a housing and mount for all the equipment involved excepting the stop members 54 and 55 and motor 44. This mechanism employs a weight 39 of considerable mass which is yieldably supported by spring 57. Intermediate between spring 57 and weight 39 is a flat bar or shutter 58 which is provided with the port or opening 60. An electric light 62 supplied from any convenient source, is positioned to show through opening 63 55 in housing 52 and on the opposite side of the housing are disposed light passageways 65 and 66 back of which are operatively disposed the light sensitive, photoelectric cells 41 and 42. Each of these lights is supplied with its own separate 60 source of electric current as 68 and 69. Normally these units consist of a current supply and amplifying means so that the current passed by the photoelectric cells may be suitably amplified to operate their respective relays 70 and 71. Relays 65 70 and 71, which are energized by the current coming from the photoelectric cells 41 and 42, control the operating motor 44, through two additional relays 74 and 75, each connected to a solenoid so arranged as to operate the reversing 70 switch 77 in a manner to operate the motor in either direction as they are selectively energized.

In order to provide for definite stopping and reversing of motor 44 at the limit of each movement of the boat, we have provided a control means for each of relays 70 and 71. These con-

trol means are identical in their construction and consist of a lever 80 pivoted at 81 and normally urged to the left as viewed in Figure 2 by compression spring 83. When so disposed the switch bars of the relays are engaged by the spring-actuated dogs 84 which are normally urged outwardly by springs 85. Each lever 80 is provided with electrical releasing means which moves the free end of the lever to the right as viewed in Figure 2 and is accomplished by the solenoids at 87 and 88. Each solenoid core is bent over at its extreme end to form the hooked members 89 and 90, probably best illustrated in Figure 1.

Assuming that the point where my device is installed in a ship is falling, due to the wave action, housing 52 is carried with the boat as it moves; weight 39, however, not being fixedly secured to housing 52 but being yieldably supported by spring 57, tends to, momentarily at least, remain stationary. This falling action causes all of the remaining parts as housing 52 light 62, and photoelectric cell 42 to move downwardly so that openings 63, 60, and 65 are in alinement; this permits the energizing of the photoelectric cell 42 by light 62 and, through the amplifier 68, relay 70 is closed. This completes a circuit energizing solenoid 88, releasing the contact bar of relay 71, if the same were closed due to moving latch 84 to the left as viewed in Figure 2 so as to release the same, and further energizes solenoid 74 which moves the reversing switch 77 into the position shown in Figure 2. This energizes the motor 44 in the direction to wind up cable 48 and thus raise room 46 with respect to its guideways 10. The speed of this travel should be balanced 35 against the movement period of the particular ship in which this equipment is installed and, for normal wave action, the cage or room 46 will be arrested, before reaching the upper extent of its travel, by a reversal of this operation due to 40 the ship itself commencing again to rise and, in this manner, the cage will be maintained on its original, horizontal plane, or very close thereto.

If, on the other hand extreme wave action is 45 encountered and the cage rises to the uppermost extent of its travel, then the solenoid arm 89 will be contacted by the cam stop member 54 in a manner to pull the solenoid to the right, as viewed in Figures 1 and 2. This will break the circuit just described due to the removal of latch 84 50 from the connector or contact bar of solenoid 70 and as weight 39 has assumed its normal position, photoelectric cell 42 will no longer be energized so as to in turn energize the relay 70. The reversal of this operation, which occurs when the 55 boat tends to rise, will be accomplished in the same manner as just described, excepting, in that instance, the boat and frame 52 will tend to rise while weight 39, observing Newton's law of motion, will tend to remain stationary. This 60 will cause openings 63, 60, and 66, to come into alinement so that light 62 may energize the photoelectric cell 41 and thus the same cycle as previously described will be accomplished so as to ultimately energize solenoid 75 and thus throw 65 the reversal switch 77 to its right hand position which, in turn, will reverse motor 44 and cause the cage, or car, to be lowered in guide 10 so that again the car will closely approximate its original horizontal position; it is believed it will be apparent, therefore, that at all times, excepting in extreme conditions, our mechanism can be so adjusted that it will maintain the car motionless while the ship moves vertically with respect thereto.

- The second action of our equipment is that of maintaining guideways 10 in a substantially vertical position as the ends of the ship change their positions due to wave action.
- 5 We have illustrated a simple form of gimbal joint 12 having a longitudinal pivot axis as 92 and a transverse pivot axis 94. The master ring of the gimbal is suitably supported as by the legs 95 from the ship structure itself.
- 10 It is desirable that the horizontal plane of the gimbal pivot be substantially at the metacenter C of the ship S which is located, in the majority of ships, approximately at the water line. Having thus mounted our guideway on a universal 15 platform it is then necessary to hold it in position and at the same time to have the holding means so arranged that it can compensate for either rolling or pitching of the boat. This is accomplished by providing preferably, attached at 20 the bottom of the guideway after the showing of the various views, a plurality of fluid operated pistons in cylinders 14. Preferably a non-compressible fluid such as oil, or water mixed with a small amount of oil, should be used so that 25 very positive holding of the guideways can be assured. The means used to effect this control is illustrated best probably, in Figures 7, 8, and 9. Here each of the cylinders 14 is, preferably, universally mounted on the ship's structure as at 30 96 and, at its opposite end, piston rod 97 of each of the cylinders is, preferably, again universally mounted at 98 at the point of its attachment to the guideway 10. This is a desirable arrangement in that the movement of the bottom of the 35 cage must be truly universal. The suction tubing 100 and the return tubing 102 must be either of a flexible character or provided with flexible joints where it attaches to the various cylinders.
- We then provide that each of the mercury 40 tube switches as 27, 28, 29, and 30, be mounted on the guideways at a slight inclination radially from the center, or vertical axis of the guideways, so that when the guideways are in a truly vertical position the mercury will run to the low 45 end of the tubes and there will be no electrical circuit completed; then let it be assumed that with the guideways in the vertical position the boat either rolls after the showing of Figure 4, or pitches, as is shown in Figure 5, then the guideways as a unit with their support will tend to move with the ship and will start to move in the same sense as the ship. If it is assumed, for instance, that the bow of the ship is lowered as going into a trough of the sea, then the forward edge of the 50 bottom of our guideway will be depressed. In the diagram of Figure 9 we have illustrated the bow of the boat to be at the bottom of the page and the stern of the boat at the top of the page. Then, as the tilting of the guideway occurs 55 switches 27 and 28 will be energized by virtue of the mercury rolling to complete the circuit through the electrodes. This action will complete a circuit energizing motors 32 connected to pumps 22 and 23 and at the same time will energize the 60 solenoid and switching arrangement at 34 and 35, closing valves 18; it will then follow that as the pump forces fluid into the rearwardly disposed cylinders 14 the bottom of the guideway structure will be forced forwardly in the 65 boat, after the showing in Figure 5, taking the first three views from the left. At the same time it is necessary that the liquid already present in the two forwardly disposed cylinders 14 be displaced; this is accomplished by the pressure exerted on the pistons through piston rods 97 and

the fluid is forced out through valves 18 due to the fact that the solenoid switching arrangements 36 and 37 are not energized and the springs that normally tend to hold these valves closed are forced open to assure free but controllable flow 5 of the fluid back through the discharge pipe 102 into the storage tank 20.

As the boat continues and passes through the bottom of the swell and starts climbing up to the next crest, a reversal of this operation takes 10 place. First, the switching means, for the motors operating pumps 22 and 23, are broken and next, switches 29 and 30 are operated which in turn energize the motors driving pumps 24 and 25. Inasmuch as the solenoid controlled valve mechanism 36 and 37 are on the same circuit as the motors, they are operated to close their valve 18 and the forward pistons can then operate, in the same manner as just described for the rear pistons, to force the bottom of guideways 10 toward 15 the rear of the ship as is illustrated on the right hand portion of Figure 5.

Combining the two actions, namely, the vertical movement of cage 46 together with the means for maintaining the guideways 10 in substantially a vertical position, will normally provide that cage 46 will be maintained substantially at a given point in space and the ship will roll or pitch without affecting this position. This can be arranged for within the limits of the 20 space available in the ship. It will follow that on large ships it would be possible to install such an arrangement so that, due to the space available the room, or cage, 46 could in effect 25 remain stationary with the ship moving with 30 respect thereto. As the size of the ship is reduced it may be necessary to merely compensate in part for the movement of the ship. This in itself would be a great help and in the majority 35 of cases would be a satisfactory solution to sea- 40 sickness encountered.

The foregoing description and the accompanying drawings are believed to clearly disclose a preferred embodiment of our invention but it will be understood that this disclosure is merely 45 illustrative and that such changes in the invention may be made as are fairly within the scope and spirit of the following claims:

1. In a stabilizing appliance for sea-going ships, the combination with a base frame, an upright 50 guide-frame, diametrically arranged pairs of fluid-pressure operated motors for stabilizing said guide frame and means responsive to certain movements of a ship for controlling said motors, and a gimbal joint between said base-frame and 55 guide-frame, of a vertically reciprocable carriage forming a compartment and suspended from the top of and within the guide frame, means for reciprocating the carriage, and means responsive to other movements of the ship for controlling 60 said reciprocating means.

2. In a stabilized appliance including a self-leveling vertically reciprocable carriage-compartment for use on a ship, the combination with a base-frame rigid with the ship, an upright guide 65 frame for the carriage-compartment, a gimbal joint located at the metacenter of the ship and joining said frames, of diametrically arranged fluid-pressure operated motors having mounts on the ship and on said guide frame below the gimbal joint, and means responsive to certain movements of the ship for controlling said motors to stabilize the guide frame on its horizontal axes. 70

3. In a stabilized appliance including a self-leveling vertically reciprocable carriage for use 75

on a ship, the combination with a base frame rigid with the ship, an upright guide frame for the carriage, and a gimbal joint located at the metacenter of the ship and uniting said frames, of diametrically arranged fluid pressure operated motors located below the gimbal joint and adapted to stabilize the guide frame on its horizontal axes, each of said motors having a loose joint mounted on the ship and a loose joint 10 mounted on the guide-frame, and means responsive to certain movements of the ship for controlling said motors.

4. In a stabilized appliance for use on a ship, the combination with a guide frame pivotally mounted at the metacenter of the ship, of diametrically arranged fluid-pressure operated motors located on the ship below the pivotal mount and adapted to stabilize the guide frame, a fluid pressure system connecting said motors, control 15 valves between said motors and said system, and electro-magnetically operated means for operating said control valves, said electro-magnetic means being responsive to certain movements of the ship.

25 5. In a stabilized appliance for use on a ship, the combination, including a base frame, an upright guide frame, and a gimbal joint between said frames mounted at the metacenter of the ship, of a carriage suspended for vertical movement in the frame, a motor-operated hoist on the frame for the carriage and an electric circuit for the motor, two electro-magnetic control devices

for the motor in said circuit, and means responsive to certain movements of the ship for separately energizing said control devices for said motor.

6. In a stabilized appliance for use on a ship, 5 the combination, including a base frame, an upright guide-frame, and a gimbal-joint between said frames mounted at the metacenter of the ship, of a carriage suspended in the frame and a hoist therefor, an electric motor for operating 10 the hoist and a circuit for said motor, two electro-magnetic control devices for said motor in the circuit, stops mounted near the opposite ends of the guide frame for co-action with said control devices, and means responsive to certain movements of the ship for operating the control 15 devices.

7. In a stabilized appliance for use on a ship, the combination, including an upright guide-frame pivotally mounted at the metacenter of 20 the ship, of a carriage suspended in the frame and a hoist therefor, an electric motor for operating the hoist and a circuit for the motor, two electro-magnetic control devices for the motor and control circuits for these devices, photo-electric cells controlling the control circuits, and an element for joint use with said cells responsive to certain movements of the ship for separately energizing said photo-electric cells.
